UNITED STATES PATENT OFFICE.

ARISTA D. WILKINSON, OF FRUITS, INDIANA.

FENCE-MACHINE.

SPECIFICATION forming part of Letters Patent No. 617,001, dated January 3, 1899.

Application filed September 3, 1898. Serial No. 690,238. (No model.)

To all whom it may concern:

Be it known that I, ARISTA D. WILKINSON, a citizen of the United States, residing at Fruits, in the county of Montgomery and 5 State of Indiana, have invented certain new and useful Improvements in Fence-Machines, of which the following is a specification.

My invention relates particularly to wire-fence machines for making wire fencing by 10 the provision of vertical pickets of steel, wire, or wood or the attachment of wire stays on horizontally-stretched line-wires, and has for its object the production of a machine of the 15 peculiar construction, combination, and arrangement of the several parts, as will be fully set forth in the following description and claims.

Referring to the accompanying drawings, 20 forming a part of this specification, in which like letters of reference indicate corresponding parts throughout the several views, Figure 1 is a side elevation of my machine entire. Fig. 2 is a transverse section of the 25 same on the line *m n*, Fig. 1. Fig. 3 is a detail plan of the inner side of an adjustable collar. Fig. 4 is a detail view of a wire-twisting sprocket-wheel. Fig. 5 is a top plan view of the adjustable operating mechanism. 30 Fig. 6 is a vertical section of the same, taken on the line *o p*, Fig. 5. Fig. 7 is a detail view of a lower detached portion of the staff for showing the long central slot through 35 which passes the endless operating-chain. Fig. 8 is a detail view of a modification of my wire-twisting sprocket-wheel. Fig. 9 is a transverse section of the same on the line *y z*, Fig. 8. Fig. 10 is a side elevation of a piece 40 of fencing produced by my machine. Fig. 11 is a side elevation of a section of fencing, showing modifications produced by my machine.

A represents the vertical supporting-staff of my machine; B, the endless operating 45 sprocket-chain; C, an adjustable collar; D, a wire-twisting sprocket-wheel; E, an adjustable operating-frame; F, a master sprocket-wheel, and G a hand-crank.

H indicates the vertical pickets of my fencing, I the horizontal line-wire, and J the wire tension-jack, which may be of the usual ordinary construction.

The vertical supporting-staff A has an upper and a lower long central slot A', through which passes the endless operating sprocket-chain B, and a handle A² at its upper end for steadyng the machine when operating the same. The endless sprocket-chain B is of the usual ordinary construction. The adjustable collar C and the wire-twisting sprocket-wheel D being duplicated several times in my machine renders a description of one of them sufficient for all. An adjustable collar C comprises two similar sections C, which have each a vertical groove C' for the reception of the staff A, a pair of through-bolts C² for rigidly securing said sections to the staff, annular openings C³ for receiving the wire-twisting sprocket-wheel D, and projecting parts C⁴, which prevent pressure of the sprocket-wheel by the sections C. The adjustable collar C may be moved longitudinally on the staff A by loosening the through-bolts C² and rigidly secured in the desired position by tightening them. The wire-twisting sprocket-wheel D, mounted between the sections C of the adjustable collar, has its peripheral edge provided with spur-teeth which mesh with the endless sprocket-chain B and at its sides annular hubs D', which fit the annular openings C³ of the adjustable collar, within which it revolves.

D² designates a central opening through the sprocket-wheel for the reception of a strand of horizontal line-wire, and D³ refers to a twisting-finger mounted rigidly in a suitable opening in the hub portion of the sprocket-wheel. The outer end of the twisting-finger D³ is provided with a deep groove D⁴, which also receives the strand of horizontal line-wire and 90 the looped portion of a vertical stay-wire picket, which it twists around the strand of line-wire, as shown in Fig. 10.

In the modification of the sprocket-wheel shown in Figs. 8 and 9 I provide two openings D⁵ within the annular hub portion on a diametric line for receiving two strands of horizontal line-wire for making what is commonly known as "picket fence" by providing a vertical picket between the line-strands 95 and then twisting the strands after the provision of the picket as much as may be desired, as shown in Fig. 11. It will also be seen from said figure that the vertical picket

may be arched or straight. In this form of the sprocket-wheel D a projecting stud D⁶ is provided for the purpose of twisting stay-wires about the double strand of line-wire, if desired.

The adjustable operating-frame E has a vertical rectangular opening E' for the reception of the staff A, a through-bolt E², which passes through a suitable opening in the wings 10 of the frame for rigidly securing it to the staff, a long slot E³ in the projecting part of the frame for the reception of the master sprocket-wheel F, and an adjustable U-shaped bearing-bracket E⁴, rigidly fixed on the projecting part 15 of the frame by means of through-bolts E⁵. The U-shaped bearing-bracket E⁴ is provided on the under side with a long rib E⁶ on each wing, which fits a long slot E⁷ at each side of the large slot E³ of the projecting part of the 20 frame for permitting the bearing-bracket to be adjusted and positioned longitudinally on the projecting part of the frame, as may be desired, without losing its alignment. The through-bolts E⁵ pass through suitable openings in the wings of the bearing-bracket E⁴, 25 with their lower portions projecting through and below the long slots E⁷ at each side of the large slot E³ of the projecting part of the frame for the purpose of rigidly securing the adjustable bearing-bracket E⁴ in the position 30 desired by tightening the nuts on the lower ends of the bolts.

E⁸ refers to transverse grooves at the inner ends of the wings of the bearing-bracket, 35 which are provided for the purpose herein-after mentioned. The master sprocket-wheel F has the usual spur-teeth at its peripheral edge and central spindles F' projecting laterally from its sides, which are adapted to fit 40 the transverse grooves E⁸ of the adjustable bearing-bracket E⁴, within which they freely rotate when manipulated with the hand-crank G. It will be seen that each end of the 45 projecting spindle F' of the master sprocket-wheel has a crank-head for the reception of the hand-crank, which permits it to be placed and operated on either end for the convenience of either a left or right hand operator. The master sprocket-wheel F meshes with the end- 50 less operating-chain B, which it impels in the direction of its own revolution. By this peculiar construction of the adjustable operating-frame E it may be vertically adjusted and rigidly positioned on the staff A by the manipulation of the through-bolt E², and its U-shaped bearing-bracket E⁴ may be longitudinally adjusted and securely positioned on its projecting part by the manipulation of the small through-bolts E⁵ for properly meshing 55 the master sprocket-wheel F with the endless chain B for operating the same.

Many different designs of fencing in details of construction may be produced with my machine; but it will suffice to show the 60 main designs in fencing produced by my machine which are necessary in common use, as is shown in Figs. 10 and 11, which are made

on a smaller scale than the other views of the drawings for the purpose of convenience.

In Fig. 10 is shown what is commonly known 70 as the "stay-twist fence," which comprises the stretched horizontal line-wire I, which may be of two or more strands, but which I have shown as comprising seven strands, and the vertical stay-wire H, which is twisted 75 around each horizontal line-strand, as shown by the operation of the wire-twisting sprocket-wheels D of my machine. H' indicates a vertical stay-wire, positioned in the proper attitude with relation to the horizontal line-wire 80 for being applied thereto by the operation of my machine, which when in position occupies an intermediate position on the horizontal line-wires I, which pass through the central openings D² of the wire-twisting sprocket-wheels between the properly-positioned vertical stay-wire H' and the tension-jack J. The vertical stay-wire has end portions H² 85 bent at right angles parallel with the upper and lower line-wire I and is provided with loops H³ at each intermediate line-wire I. The end portions H² and the loops H³ are inserted into the deep grooves D⁴ of the twisting-fingers D³ of the sprocket-wheels D, which wind them about the horizontal line-wires I, as shown at H⁴ H⁴ in Fig. 10, by the operation of my machine.

In Fig. 11 is shown what is usually termed "picket fence," which comprises the horizontal line-strands I, which I have shown as seven 100 in number, but which may be of two or more strands and the vertical pickets H⁵ secured 105 therein. It will be seen that the vertical pickets H⁵ may be arched or straight and that the horizontal line-strand I consists necessarily of two wires which pass through the two small openings D⁵ of the modification of the wire-twisting sprocket-wheels shown in Figs. 8 and 9, which twist the two wire strands about the vertical picket H⁵ as often as may 110 be desired by the operation of my machine, which is positioned on the horizontal line-strands between the vertical pickets which have been applied and the tension-jack ordinarily used in stretching and holding the horizontal line-strands.

The tension-jack J, which I do not claim as a part of my invention, is merely shown to indicate that the free ends of the horizontal line-wire and strands are connected, as usual, 120 with an ordinary tightening and holding device, which it is unnecessary for me to describe in detail. The other end of the line-wire and strand, as is the usual custom, is attached to an ordinary end or anchor post and the intermediate portion with line-posts.

My invention is operated as follows: The endless sprocket-chain B passes over the upper and lower wire-twisting sprocket-wheels and alternately in the front and the rear of the intermediate sprocket-wheels and through the long central slots of the staff around the master sprocket-wheel, which imparts motion to each wire-twisting sprocket-wheel when

the master sprocket-wheel is revolved with the hand-crank by the operator. The motion of the sprocket-wheels twists the end portions and intermediate loops of the vertical stay-wire positioned in its proper attitude about the horizontal line-wire, which passes through the central openings of the sprocket-wheels. In the modification of the wire-twisting sprocket-wheels in my machine the line-strands necessarily consist of two wires to a strand, and also pass through the central openings of the sprocket-wheels, the wire strands being wound about the vertical pickets which pass between each wire of the line-strand and rigidly secure the picket in the desired position. The vertical pickets, vertical stay-wire, and my machine are positioned in proper relation to the horizontal line wires and strands, as has been fully described hereinbefore.

Having thus fully described my machine and set forth the operation and advantages thereof, what I claim as my invention, and desire to secure by Letters Patent, is—

25 1. A fence-machine comprising a vertical staff having a handle and long central slots at its upper and lower end, a series of adjustable collars mounted on the staff and having two similar sections in each collar provided with 30 a pair of through-bolts, vertical grooves, annular openings and projecting parts for the purpose named, a series of wire-twisting sprocket-wheels revolvably mounted in the annular openings of the adjustable collars and 35 having spur-teethed peripheries, annular hubs, central openings, and projecting fingers provided with deep grooves as and for the purposes set forth, an adjustable operating-frame mounted on the staff having a vertical 40 rectangular opening, a through-bolt, a projecting part provided with a long central slot and long narrow slots at each side of the central slot, a U-shaped bearing-bracket provided with ribs on the under side of each wing and

through-bolts for rigidly securing it to the frame as and for the purpose set forth, a master sprocket-wheel provided with central projecting spindles which are mounted in the transverse grooves of the adjustable operating-frame, an endless sprocket-chain which 50 encircles the master sprocket-wheel and the wire-twisting sprocket-wheels in the manner and for the purpose set forth, and means for operating the same, all substantially as shown and set forth.

55 2. In a fence-machine, the combination of a vertical staff, a series of adjustable collars, each collar composed of two sections and provided with vertical grooves, a pair of through-bolts, annular openings and projecting parts 60 for the purpose named, a series of wire-twisting sprocket-wheels mounted in the annular openings of the adjustable collars and having spur-teethed peripheries, annular hubs, central openings and twisting-fingers provided 65 with deep grooves as and for the purpose set forth and means for operating the same, substantially as specified.

3. In a fence-machine, the combination of the vertical staff, a series of adjustable collars, 70 each collar composed of two similar sections, a series of revoluble wire-twisting sprocket-wheels mounted in the annular openings of the adjustable collars made in the manner and for the purposes set forth and an adjustable operating-frame securely mounted on the vertical staff having a vertical opening, a through-bolt, a projecting part provided with a long central slot and narrow slots at each side of the central slot a U-shaped bearing- 75 bracket provided with ribs on its under side and through-bolts for securing it to the projecting part and means for operating said parts, all as and for the purposes set forth.

ARISTA D. WILKINSON.

In presence of—

OLIVER U. PERRIN,
J. M. WILLIS.
